UNITED STATES PATENT OFFICE.

ARTHUR J. PARENT, OF MENOMINEE, MICHIGAN, AND FRANK J. LAUERMAN, JR., OF MARINETTE, WISCONSIN.

TIE BOX.

Application filed December 3, 1923. Serial No. 678,179.

To all whom it may concern:

Be it known that we, ARTHUR J. PARENT and FRANK J. LAUERMAN, Jr., both citizens of the United States, and residents of Me-
5 nominee and Marinette, respectively, in the counties of Menominee and Marinette, re-
spectively, and States of Michigan and Wis-
consin, respectively, have invented certain
new and useful Improvements in Tie Boxes;
10 and we do hereby declare that the following is a full, clear, and exact description thereof.

This invention relates to necktie boxes.

In necktie boxes, as usually constructed, it has been the practice to provide merely an elongated pasteboard box within which a single necktie is carried. When it is desired to display this necktie, the box is customarily stood on end at a sharp slant and the necktie thus disposed to view. However, the necktie frequently slips down, or sags in the box, and presents an unsightly appearance which materially detracts from the efficacy of the display.

It is to overcome the above noted defects
25 that this invention is designed, and objects
of this invention are therefore to provide a
necktie box which will receive and house
the necktie in the usual manner while at the
same time holding the necktie in the correct
30 position for display purposes, although the
box may be stood on end and inclined at a
very great angle to the horizontal.

Further objects are to provide a necktie box in which the desirable feature of holding the necktie in a smooth and attractive manner, when on display, is secured without material increase in the cost of the box and without detracting from the ease with which the necktie may be positioned within such box.

An embodiment of the invention is shown in the accompanying drawings, in which Figure 1 is a front view of the box with the top removed and positioned upon the rear side of the bottom of the box, showing the necktie in its displayed position.

Figure 2 is a fragmentary section on the line 2-2 of Figure 1.

Figure 3 is a corresponding section on the line 3-3 of Figure 1.

The box comprises the usual bottom portion, indicated generally at 1, and the top 2.

which normally closes the box, which, as shown in Figure 1, may be positioned rearwardly of the bottom portion for display purposes. Within the upper end of the bottom portion a transverse, flexible tape, preferably of fabric, as indicated at 3, is provided, and has its ends passed through apertures 4 punched through the side walls 5 of the bottom 1. This tape has its extreme ends 6 bent rearwardly over the bottom, prior to the positioning of the finishing paper, or facing piece. This finishing paper 7 is thereafter pasted over the box, as clearly shown in Figures 2 and 3, and thus secures the ends 6 of the strip 3 in position and hides such ends. 65

In using the box the tie is preferably folded in the usual manner and the portion 8 passed downwardly behind the tape 3, as shown in Figure 3, thus positioning the main portion 9 of the tie in an exposed position. It will be seen, therefore, that when the distributor receives the tie that he may either remove the top, or position it rearwardly of the bottom and display the tie in an attractive manner by standing the box on end, thus allowing the tie to hang freely from the strip or tape 3 and preventing any sagging whatsoever, but instead allowing the tie to hang downwardly in a free and smooth manner.

It will thus be seen that a tie display box has been provided, in which the additional advantage of correctly displaying the tie is secured without materially increasing the cost of manufacture of the box on the one hand, and without requiring any difficult manipulation of the tie on the other hand. 90

Although the invention has been described in considerable detail, it is to be understood that it may be variously embodied and is therefore to be limited only as claimed.

We claim:—

1. A necktie display box comprising a bottom portion, a top therefor, a tape extending transversely of said bottom portion and having its ends projecting therethrough and folded flat against the outer side thereof, and a finishing piece pasted upon the outer side of said bottom portion and hiding and securing the ends of said tape. 95 100

2. A necktie display box comprising an

elongated bottom portion and correspondingly shaped top portion, a tape extending transversely across said bottom portion adjacent one end thereof and having its ends passed through apertures formed in the side walls of said bottom portion and folded flatly against the rear side of said bottom portion, and a finishing piece pasted over

said bottom portion and hiding and securing the outer ends of said tape. 10

In testimony that we claim the foregoing we have hereunto set our hands at Marinette, in the county of Marinette and State of Wisconsin.

ARTHUR J. PARENT.
FRANK J. LAUERMAN, JR.
